UNITED STATES PATENT OFFICE.

HENRY C. MAXWELL, OF ROME, NEW YORK.

CHECK-BIT.

SPECIFICATION forming part of Letters Patent No. 269,304, dated December 19, 1882.

Application filed October 30, 1882. (No model.)

To all whom it may concern:

Be it known that I, HENRY C. MAXWELL, a citizen of the United States, residing at Rome, in the county of Oneida and State of New York, have invented a new and useful Check-Bit, of which the following is a specification, reference being had to the accompanying drawings.

Figure 1 is a perspective view of my improved bridle-bit. Fig. 2 is a longitudinal sectional view, and Fig. 3 is an end view.

The same letters refer to the same parts in all the figures.

This invention relates to check-bits for harness; and it consists in certain improvements in the construction of the same, whereby the lines may be readily attached or detached without sewing or the use of separate buckles, and by which a useful and comfortable bit is produced which is not liable to injure the horse's mouth, as will be hereinafter fully described, and particularly pointed out in the claims.

A in the drawings represents the body of my improved bit, which consists of a round bar of suitable dimensions. The ends B are bent at right angles to the body A and flattened so as to form plates, each of which is provided with two horizontal slots, C, so as to form practically a buckle-frame with a cross-piece or bridge, D, separating the said slots. Said cross-piece D is provided with an outwardly-projecting stud, e. The plates B are

provided on their inner sides, just above the bar A, with shallow recesses F to receive the ends of the lines G, which are shaved down 35 thin, so as to be readily accommodated in said recesses. The lines G are provided near their ends with perforations H, which, when the said ends are passed through the slots C C, fit over the studs e, and thus serve to connect the 40 lines with the bit. The ends of the lines, being accommodated in the recesses F, are flush with the inner sides of the plates B, and consequently do not gall or irritate the mouth of the horse.

My improved bit is simple, inexpensive, and may be easily and quickly connected with or detached from the lines without the use of separate buckles or stitching.

I claim as my invention—

1. The bit A, having flattened ends B, provided with slots C, and cross-pieces D, having studs e, as set forth.

2. The bit A, having flattened ends B, provided with slots C, cross-pieces D, having studs 55 e, and recesses F, as set forth.

In testimony that I claim the foregoing as my own I have hereto affixed my signature in presence of two witnesses.

HENRY CLAY MAXWELL.

Witnesses:
